UNITED STATES PATENT OFFICE.

FRANK S. McCULLOUGH, OF SAN FRANCISCO, CALIFORNIA.

EGG CASE.

Application filed April 20, 1921. Serial No. 462,976.

To all whom it may concern:

Be it known that I, FRANK S. McCULLOUGH, a citizen of the United States, and a resident of the city and county of San Francisco, California, have invented a new and useful Egg Case, of which the following is a specification.

This invention relates to receptacles and more particularly to shipping cases such as are employed for the packing and shipping and storage of eggs.

It is one of the objects of the present invention to provide an egg case of such construction that the arrangement and packing of tiers of cardboard racks with eggs may be greatly facilitated and it is, as well, an object to provide for the facile removal of each rack or tier of eggs from the case as may be desired particularly in the successive removal and replacement of tiers of eggs and their racks for purposes of examination, processing or other handling.

A further object of the invention is to provide an egg shipping case that is of extremely simple construction, is of few and substantial parts and is capable of being readily assembled and secured in a closed position of its parts.

A further object of the invention is to provide an egg shipping case having a substantial wall structure open at the top and at one side and having means to slidably interlock to close the open side and having a cover to be secured in place after the closure at the open side has been applied.

The invention possesses other objects and features of advantage, some of which with the foregoing, will be made manifest in the following description of the preferred form of the invention which is illustrated in the drawings accompanying and forming part of the specification. It is to be understood that it is not intended to limit the invention to the embodiment shown by the said drawings and description as variations may be adopted within the scope of the invention as set forth in the claim.

Fig. 1, is a perspective of the assembled and closed case; a portion of the top being broken away.

Fig. 2, is a perspective of an end wall showing the rebated inner corner.

Fig. 3, is a perspective of the detached side closure or panel.

Fig. 4, is a perspective of the detached top.

It is the common practice to market eggs in cases of suitable dimensions in which there is generally a dividing wall extending transversely across the case between its ends 60 thus forming subdivisions of the case chamber and in each of these subdivisions eggs are arranged in superposed horizontal tiers; the eggs being maintained in separate relation in cellular racks usually of pasteboard and each of the racks with its contents of eggs is separated vertically by a piece of pasteboard, which forms the bottoms of the cells of the racks. The cases commonly have rigidly secured end walls 70 and parallel side walls so that the tiers of eggs and racks are successively built up from the bottom in the case compartments and then the case is closed at the open upper portion by a top. 75

This requires considerable care and time in the stacking of the eggs. In some egg handling establishments it is the practice to examine, or process or transfer the eggs and to replace them in the same or other cases and the present invention consists of a case of such construction that the removal and insertion of the arranged eggs in each tier can be quickly and safely done by a direct, horizontal, lateral movement 80 from the case instead of the slow and difficult system practiced of taking the tiers one after the other from the top downwardly in unloading the case. Conversely the present invention provides for the rapid 90 loading and replacing of tiers of eggs in a case by lateral, horizontal movement of each tier inwardly to its proper position in the case. 95

A preferred embodiment of the invention is shown as consisting of a case having substantial end walls 2-2, re-enforced transversely by outside cleats 3, and at the lower ends of the end walls is secured a suitable bottom 4, and one longitudinally extending 100 side wall 5, is rigidly secured to the ends 2-2, and the bottom 3. A dividing partition 6, is secured to the side wall 5, and to the bottom 4. This construction therefore provides one open side and the open top or upper end of the case, which latter is closable by a simple and suitable top or cover 7, shown in the present case, as having on its lower face inwardly extending cross bars 8-8, fitting over the upper ends of the end panels 2, and approaching the contiguous upper re-enforcing strips 3. The top or 105 110

cover 7, may be further re-enforced by cross pieces 9—9.

For the purpose of closing the open side of the case opposite to the fixed side 5, a removable and loosely retained side panel 10, is provided, the vertical ends of which are designed to readily slide into vertical channels or rebates 11, provided to receive the same in the inner faces of the end walls 2. 10 Preferably the removable side panel 10, is re-enforced by vertical cleats 12, contiguous to the ends that are insertible into the rebates 11, of the walls.

For the purpose of staying the upper corners of the end walls at the open side of the case they are connected as by a longitudinally extending stay strip as a tape-like metal 13, the ends of which are secured to the outer surface of the end walls 2—2 and 15 may be covered by the contiguous portion of the re-enforced cleats 3. The stay strip 13, is designed to reach across the upright reinforcing cleats 12, of the removable panel 10, and is preferably bent or flexed inwardly 20 as at 13^a, so as to approach the surface of the panel 10. This arrangement tends to prevent the stay strip 13, from bending outwardly or forwardly and protects it against entanglement with foreign obstacles. 25

From the above it will be seen that the present case may be quickly packed with

tiers of eggs while the side panel 10, is removed and before the cover 7, is applied and enables the ready removal of the tiers of eggs with their racks by a longitudinal, lateral shifting of each of the tiers while the side panel is removed. After the desired processing or handling of the tiers of eggs has been accomplished and the case has again been loaded, the side panel 10, is slid 35 into its position interlocking in the rebates 11, of the end panels 2, and then the cover or top 7, is applied and may be nailed, stapled or otherwise fastened as to the top edges of the end walls 2. 40 45

What is claimed is:

An egg case comprising rigidly connected end walls, bottom and longitudinal side providing an open side and an open top, the end walls at the open side being provided on their inner faces with vertical grooves, a longitudinal side adapted to be slipped downward in said grooves to close the open side, a top closure and a longitudinal stay strip secured to the end walls adjacent their upper edges and extending across the open side of the case in front of the removable longitudinal side. 50 55

In testimony whereof, I have hereunto set my hand.

FRANK S. McCULLOUGH.
